FRANK C. ANDERSON, OF CINCINNATI, OHIO.

SWITCH-STAND TARGET MECHANISM.

1,108,659.

Specification of Letters Patent. Patented Aug. 25, 1914.

Application filed October 15, 1913. Serial No. 795,221.

To all whom it may concern:

Be it known that I, FRANK C. ANDERSON, a citizen of the United States, residing at Cincinnati, in the county of Hamilton and 5 State of Ohio, have invented certain new and useful Improvements in Switch-Stand Target Mechanisms, of which the following is a specification.

My invention relates to target mechanisms 10 for switch stands of the skeleton or rotary type and has for its object the complete change of the target to "danger" position before opening of the switch can be commenced; and also to lock the target mech- 15 anism so that it cannot be brought back to "safety" position until the switch has been completely thrown back to its safe position.

My invention consists in the parts and 20 in the details of construction and arrangement of parts as will hereinafter be more fully described and claimed.

In the drawings: Figure 1 is a side elevation of a switch stand and target embodying my invention, the parts being locked in 25 safe position and the target shaft being represented as having part broken away on account of lack of space; Fig. 2 is a detail perspective view of the switch operating lever, the target operating lever in engagement 30 therewith, and part of the target connection pivoted to the target-operating lever; Fig. 3 is a plan view of the device, the parts being in safety position as in Fig. 1; Fig. 4 is a plan view similar to Fig. 3, but with the 35 parts in danger position; and Fig. 5 is a partial cross section on the line $x-x$ of Fig. 4.

The switch stand 1 has the main shaft 2 journaled vertically in it, being held in upper and lower bearings by caps 3 and 4, respectively. Below the lower bearings, this shaft has the crank 5 with the crank pin 6, which is adapted to receive the connecting rod which is connected to the point rails 45 of the switch. Above the upper bearing, this main shaft 2 has fixed on it the fulcrum-head 7, said main shaft being supported by this fulcrum-head 7 bearing down against the upper side of the upper 50 bearing. The fulcrum-head 7 has the switch-operating lever or handle 8 pivotally swinging on the pivot 9. The top of this switch stand 1 comprises the horizontal plate 10, which has slots 11 and 12 diametri- 55 cally opposite on a line through the center

of the main shaft 2, and the handle or lever 8 is adapted to engage in either one of these slots when the switch is completely thrown one way or the other. The handle or lever 8 has the ear 13 above its pivot 9, with an opening 14 adapted to receive the bow or shackle of the padlock to engage against the outer face of the fulcrum head 7, whereby the lever 8 may be locked against removal from the slot 11 or slot 12 as the case may 60 be. It will be seen that the main shaft 2 is thus rotated 180° to throw the switch, and the mechanism so far described is similar to previously disclosed apparatus in switch stands. 70

The target shaft 15 is journaled vertically, parallel with the main shaft 2 in upper and lower brackets 16 and 17, respectively, which are bolted to the switch stand 1 along with the caps 3 and 4, respectively, 75 of the upper and lower bearings of the shaft 2. These brackets not only extend outwardly some distance from the main shaft but are also offset somewhat, as is best seen in Figs. 3 and 4. Above the upper bracket 80 16, a slotted arm 18 is pinned or otherwise suitably fixed to the target shaft 15, and, by bearing against the upper side of the bracket 16, supports the target shaft. The upper end of the target shaft carries the 85 blades 19 and 20 extending at right angles to each other and adapted, respectively, when turned in directions crosswise of the track, to signal "safety" or "danger". It will thus be seen that the target shaft 15 is 90 to be rotated through only 90° .

To operate the target, a target-operating lever 21 has a pivot 22 in one of two stops 23 and 24 which are provided on the plate 10 for the fulcrum-head 7. This pivot 22 95 is concentric with the pivot 9 of the switch-operating lever or handle 8. Projecting from the side of the target-operating lever 21, toward the switch-operating lever 8, is a boss 25 that carries a lug 26, and the switch-operating lever 8 has a slot 27 that receives the lug 26, whereby the target-operating lever 21 is moved along with the switch-operating lever 8, the two levers 100 swinging together on their concentric pivots 9 and 22. 105

A bifurcated connection-head 28 flanks the slotted arm 18 above and below, and a pin 29 passes down through this head 28 and slides in the slot 30 of the arm 18. This head 28 110

has, projecting over toward the target-operating lever 21, a lug 31 and a bifurcated socket 32 flanks this lug 31, with a pin 33 passing horizontally through them, thus 5 pivoting them together so that the socket 32 can swing on the head 28 in a vertical plane. A rod 34 is screwed into the socket 32 and has a lock-nut 35 to hold it stationary therein; this rod 35 has an eye 36 which 10 is received between bifurcations 37 on the upper end of the target-operating lever 21, and a pin 38 passes through the bifurcations 37 and through the eye 36, thus pivoting the rod 34 and the lever 21 together. This rod 15 34 and the socket 32 make up a connecting rod between the target-operating lever 21 and the head 28 which, engaging with the slotted arm 18, rotates the target shaft through its quarter-revolution when the 20 lever 21 is swung upward through a quarter-revolution. By having the rod 34 screwed into the socket 32, it is possible to adjust the length of the connecting rod thus made up, and, by means of the nut 35, this 25 connecting rod may be made rigid at any adjustment. Such adjustment not only allows the parts to be accurately positioned during assemblage of the mechanism, but also allows adjustment to compensate for 30 wear in the parts after the mechanism has been in use for some time. To form a guide for the head 28 during its initial movement, a lug 39 is provided on the bracket 16, slightly outside the head 28. Such a guide 35 is desirable especially in view of the tendency of this connection to be displaced outwardly during initial movement as the pin 29 bears against the side of the slot 30 in the arm 18, which in this position is inclined 40 to the line of movement at an angle of 45°. After the parts have moved so far that the arm 18 is approaching a position at right angles to the line of movement, this tendency becomes negligible, and toward the 45 other end of the movement the tendency is for the connection to be displaced in the other direction. This tendency is counteracted by another guide which will be referred to later.

50 When the switch is to be thrown, the first act of the operator, after removing the padlock from the ear 13, is to bring the handle or lever 8 to a horizontal position, swinging on its pivot 9, and with its upper 55 end, carrying the ear 13, moving down into the interior of the fulcrum-head 7. When this lever has reached this horizontal position it is completely out of the slot 11 or 12 as the case may be. This lever 8, together 60 with the fulcrum-head, now make up the operating lever of the switch stand, and they are swung around over the plate 10 through the required 180°, whereupon the handle or lever 8 is dropped into the slot 65 12 or 11 at the other side, as the case may be.

As shown in the drawings, the switch stand is so designed that when the lever 8 is in the slot 11 it will have closed the switch and the "safe" or "clear" signal will be required of the target. Now, as the lever 8 is raised out of the slot 11, it will raise the target-operating lever 21 with it, as before described, which will result in turning the target shaft through the quarter-revolution required to effect the change of signal from "safe" or "clear" to "danger." This completion of the change of signal will occur just as the lever 8 reaches its horizontal position out of engagement with the sides of the slot 11. Then the switch may be thrown, 70 the lever 8 being brought around to the other side of the stand and dropped into the slot 12 thereat.

While the mechanism so far described insures that the target will be operated from "safe" to "danger" position before throwing of the switch is commenced, it will not, in itself, prevent throwing of the target back to "safe" position before the switch itself is thrown back to such position; it 80 will be seen that it would be possible to operate the target by means of the target-operating lever 21 itself after the switch operating lever 8 had been disengaged therefrom. To prevent this operation of the target mechanism independently of the switch operating mechanism, I provide a segment 40 on the fulcrum-head 7, concentric with the shaft 2. This segment is so positioned that when the fulcrum-head is in position 90 to permit the lever 8 to occupy the slot 11, the segment will have a terminal part 41 lying alongside the line of movement of the connection head 28. This part occupies such a position along this line of movement that 100 it will provide the guide for the head 28 on its other side, in the region where the tendency is to displace the connection of which the head 28 forms part, as hereinbefore al-luded to. The segment 40 extends around 110 from this terminal part 41 to the other side of the fulcrum-head 7, where it merges with the side of the fulcrum-head. To properly engage with the edge of the segment 40, the upper bifurcation of the head 28 is made 115 considerably higher than the lower one, as is best seen in Figs. 1 and 5. The socket 32, connected to the head 28, is thus enabled to pass under the segment 40 on account of the segment being placed in elevated position and the head 28 being extended up to 120 engage with the segment.

The terminal part 41 of the segment 40, being so close to the line of movement of the head 28, it will be seen that as soon as 125 any appreciable rotation of the main or switch-operating shaft 2 occurs, this segment 40 will begin to obstruct the path which the head 28 would be compelled to follow in a return movement to return the 130

target to "safe" position. With the segment 40 disposed as described, it will thus obstruct the return movement of the target-operating connection while the switch-operating mechanism is in any position around 5 its 180° of travel, clear up to the extreme other position with the lever 8 in the slot 12. It will not be possible to return the target-operating mechanism to "safe" position 10 until the switch-operating mechanism has been brought entirely back, so that the switch is safely closed.

It will be understood that when the switch-operating lever 8 returns, in its horizontal position, the target-operating lever 21 15 will be found also in horizontal position and the slot 27 in the lever 8 will receive the lug 26 of the lever 21; and then when the switch-operating lever 8 is brought down to vertical position, the target-operating mechanism 20 will be operated back, bringing the target back into safe position as the switch-operating lever 8 is brought down into position for locking again. It will not be possible 25 to lock this lever 8 until the opening 14 in the ear 13 has been brought far enough out of the fulcrum-head 7 to admit the shackle of the padlock. Not until this has occurred will the target have been brought 30 completely into "clear" or "safe" position. It is thus seen that the operator is compelled to bring the target into "safe" position before he can lock the switch, so that display 35 of "danger" by the signal when the switch is safe is also prevented, as well as the more serious irregularity of displaying "safety" when the switch is open, which is prevented in the manner above described.

It will be noted that until the lug 26 of the 40 target operating lever 21 is entirely withdrawn from the slot 27 in the switch operating lever 8, it is impossible to operate the target independently of the switch operating lever 8 even though the segment 40 did not 45 come within the path of the operative connection to the target. Thus double protection is afforded at this period of the operation of the switch mechanism, amply guarding against false removal of the target from 50 "danger" position even though the segment 40 should fall somewhat short of promptly performing its duty in this period of the operation.

I have illustrated and described a switch 55 stand requiring a rotation of the main shaft through 180° but since the target mechanism is completely operated before the operation of the switch mechanism is commenced, it is immaterial what degree of movement the 60 switch stand mechanism requires in throwing the switch. Some switch stands require a rotation of the main shaft through only 90°, and others may involve more or less degree of rotation; but my improved target 65 operating and locking mechanism may be

incorporated in such a switch stand with the parts properly proportioned, and will operate correctly according to the principle herein set forth in such a switch stand mechanism.

As shown in the drawings, the bracket 16 is made with the guides 39 both above and below, so as to permit the bracket being inverted where it is desired to have a right-hand instead of the left-hand switch stand. 70 The lower bracket 17 is also invertible in making a switch stand for such reverse position, and the target-operating lever 21 would be pivoted on the stop 24 at the other side of the stand and the other parts would be 75 arranged accordingly. The only part requiring a different part to be substituted for it will be the fulcrum-head 7 with its segment 40. The fulcrum-head to operate on the other side requires its segment to be 80 placed diametrically opposite.

The above details are referred to in order to make clear the illustration of my preferred construction. However, it will be understood that such details may be altered 90 and various other minor changes may be made without departing from the scope or spirit of my invention as set forth in the following claims.

1. In combination with a switch stand and a target thereon, a switch-operating element requiring initial movement in one plane before being movable in another plane to operate the switch, a target shaft, a target-operating lever, means for operative engagement between the switch-operating element and the target-operating lever whereby the lever moves with the switch-operating element during the initial movement of the switch-operating element, an arm with which the target shaft turns, and operative connection from the target-operating lever to this arm, whereby said target is completely operated during said initial movement of the switch-operating element. 95

2. In combination with a switch stand and a target thereon, a switch-operating element requiring initial movement in one plane before being movable in another plane to operate the switch, a target shaft, a target-operating lever, means for operative engagement between the switch-operating element and the target-operating lever whereby the lever moves with the switch-operating element during the initial movement of the switch-operating element, an arm with which the target shaft turns, operative connection from the target-operating lever to this arm, whereby said target is completely operated 100 during said initial movement of the switch-operating element, means moved by said switch-operating element into the path of travel of the operative connection between the target-operating lever and the arm of the target shaft, whereby operation of the target 105 110 115 120 125 130

independently of the operation of the switch-operating element is prevented.

3. In combination with a switch stand and a target thereon, a switch-operating element requiring initial movement in one plane before being movable in another plane to operate the switch, disengageable operative connections between this element and the target, whereby the target is completely operated during said initial movement of said element, means carried along with said element in its switch-operating movement, and thereby projected into the path of travel of said operative connection, whereby operation of said operative connection to operate the target independently of the operation of said element is prevented, stationary guiding means on said switch stand for the operative connection, said means carried along with said element forming another guiding means for the operative connection during said initial movement of said element.

4. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum-head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, and operative connection between this target-operating lever and said target shaft, whereby said target is completely operated during said initial swinging of the switch-operating lever.

5. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum-head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, an arm fixed on the target shaft, and operative con-

nnection between the target-operating lever and said arm, whereby the target is completely operated during the initial swinging of said switch-operating lever.

6. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum-head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, an arm fixed on the target shaft, a connection-head articulating with said arm, and connection between said connection-head and said target-operating lever, whereby the target is completely operated during said initial swinging of said switch-operating lever.

7. In combination with a switch stand and a target thereon, a main switch-operating shaft, a fulcrum-head fixed to rotate said main shaft, a switch-operating lever pivoted in the fulcrum-heads, a stationary plate having a slot, said switch-operating lever being received in the slot and requiring to be initially swung on its pivot in the fulcrum-head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, an arm fixed on the target shaft, a connection-head articulating with the arm, and a connecting element pivoted to said connection-head and to said target-operating lever, whereby the target is completely operated during said initial swinging of said switch-operating lever.

8. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum-head to disengage from the slot and permit rotation of the fulcrum-head and main shaft, a target shaft parallel to said main shaft, a

target-operating lever pivoted concentric with the pivoting of the switch-operating lever, means for operative engagement between the switch-operating lever and this target-operating lever, whereby the two levers swing together during the initial movement of said switch-operating lever, an arm fixed on the target shaft, a connection-head articulating with the arm, and a connecting element pivoted to said connection-head and to said target-operating lever, whereby the target is completely operated during said initial swinging of said switch-operating lever, and means for adjusting the length of said connecting element.

9. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, operative connection between this target-operating lever and said target shaft, whereby said target is completely operated during said initial swinging of the switch-operating lever, and means on said fulcrum-head adapted to project into the path of travel of said operative connection when the fulcrum-head is rotated to operate the switch.

10. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum-head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, an arm fixed on the target shaft, a connection-head articulating with said arm, and connection between said connection-head and said target-operating lever, whereby the

target is completely operated during said initial swinging of said switch-operating lever, and means on said fulcrum-head projecting into the path of travel of said connection-head, whereby operation of the target independently of the operation of the switch-operating mechanism is prevented.

11. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum-head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, an arm fixed on the target shaft, a connection-head articulating with the arm, a connecting element pivoted to said connection-head and to said target-operating lever, whereby the target is completely operated during said initial swinging of said switch-operating lever, and means on said fulcrum-head projecting into the path of travel of said connection-head, whereby operation of the target independently of the operation of the switch-operating mechanism is prevented.

12. In combination with a switch stand and a target thereon, a main switch-operating shaft, a fulcrum-head fixed to rotate said main shaft, a switch-operating lever pivoted in the fulcrum-head, a stationary plate having a slot, said switch-operating lever being received in the slot and requiring to be initially swung on its pivot in the fulcrum head to disengage from the slot and permit rotation of the fulcrum-head and main shaft, a target shaft parallel to said main shaft, a target-operating lever pivoted concentric with the pivoting of the switch-operating lever, means for operative engagement between the switch-operating lever and this target-operating lever, whereby the two levers swing together during the initial movement of said switch-operating lever, operative connection between this target-operating lever and said target shaft, whereby said target is completely operated during said initial swinging of the switch-operating lever, means on said fulcrum-head adapted to project into the path of travel of said operative connection when the fulcrum-head is rotated to operate the switch, and a guide for the operative connection at

one side thereof on the switch stand, said projecting means on the fulcrum-head acting as a guide for said operative connection at the other side during the initial swinging 5 of the switch-operating lever.

13. In combination with a switch stand and a target thereon, a main switch-operating shaft, a fulcrum-head fixed to rotate said main shaft, a switch-operating lever 10 pivoted in the fulcrum-head, a stationary plate having a slot, said switch-operating lever being received in the slot and requiring to be initially swung on its pivot in the fulcrum-head to disengage from the slot 15 and permit rotation of the fulcrum-head and main shaft, a target shaft parallel to said main shaft, a target-operating lever pivoted concentric with the pivoting of the switch-operating lever, means for operative 20 engagement between the switch-operating lever and this target-operating lever, whereby the two levers swing together during the initial movement of said switch operating lever, an arm fixed on the target 25 shaft, a connection-head articulating with said arm, connection between said connection-head and said target-operating lever, whereby the target is completely operated during said initial swinging of said switch-operating lever, means on said fulcrum-head 30 projecting into the path of travel of said connection-head, whereby operation of the target independently of the operation of the switch-operating mechanism is prevented, and a guide for said connection-head 35 on the switch stand at one side of the head, said projecting means on the fulcrum head acting as a guide for said connection-head at its other side during the initial swinging 40 of the switch-operating lever.

14. In combination with a switch stand and a target thereon, a main switch-operating shaft, a fulcrum-head fixed to rotate said main shaft, a switch-operating lever 45 pivoted in the fulcrum-head, a stationary plate having a slot, said switch-operating lever being received in the slot and requiring to be initially swung on its pivot in the fulcrum-head to disengage from the slot 50 and permit rotation of the fulcrum-head and main shaft, a target shaft parallel to said main shaft, a target-operating lever pivoted concentric with the pivoting of the switch-operating lever, means for operative 55 engagement between the switch-operating lever and this target-operating lever, whereby the two levers swing together during the initial movement of said switch-operating lever, an arm fixed on the target shaft, a 60 connection-head articulating with the arm, a connecting element pivoted to said connection-head and to said target-operating

lever, whereby the target is completely operated during said initial swinging of said switch-operating lever, and means on said fulcrum-head projecting into the path of travel of said connection-head, whereby operation of the target independently of the operation of the switch-operating mechanism is prevented, and a guide for said connection-head on the switch stand at one side of the head, said projecting means on the fulcrum-head acting as a guide for said connection-head at its other side during the initial swinging of the switch-operating 75 lever.

15. In combination with a switch stand and a target thereon, comprising an upright main shaft and an upright target shaft, means for rotating the main shaft, and means coöperating with the main-shaft-rotating means to rotate the target shaft, a bracket for the target shaft extending out away from said main shaft and having an offset over to the target shaft, a projection on said bracket forming a guide for the means that operates the target shaft, said target-operating means being transposable on said switch stand and said bracket being reversible thereon to accord with the transposition of said parts, and a companion projection on the other side of said bracket to guide the target-operating means when the bracket is inverted.

16. In combination with a switch stand 95 and a target thereon, a main shaft, means for rotating the main shaft, a target shaft, a slotted arm fixed to the target shaft, a bifurcated connection-head flanking the slotted arm, a pin in said head engaging with 100 the slot of the arm, a lug on said connection, a bifurcated socket flanking the lug, a pin passing through the bifurcations of the socket and through said lug and pivoting the socket and the head together, a rod adjustably secured in said socket, a bifurcated target-operating lever having its bifurcations flanking said rod, a pin passing through these bifurcations and through the rod, a stop on the switch stand for the 105 switch-operating mechanism, a pivot for said target-operating lever in said stop, and means for engagement between the switch-operating means and said target-operating lever, whereby this lever is swung on its 110 pivot to rotate said target shaft through the medium of said rod, said socket, said connection-head and said slotted arm, during part of the operation of the switch-operating mechanism, for the purposes set forth. 115 120
